REVERSIBLE RATCHET CAM SLOT DRAWOUT MECHANISM FOR SWITCHGEARS

Warren J. Donaldson, Upper Darby, Pa., assignor to General Electric Company, a corporation of New York

Application August 1, 1951, Serial No. 239,706

15 Claims. (Cl. 200—50)

The invention relates to metal-enclosed drawout switchgear and the principle object is to provide improved force amplifying manually operable insert and drawout, lock and interlock mechanisms particularly suitable for an automatic circuit breaker mounted on a carriage to form a completely removable switchgear unit that is provided with disconnect contacts whereby the breaker is connected to and disconnected from the circuit by insertion and withdrawal movement of the unit in a suitable metal enclosing unit or cubicle having cooperating circuit terminal contacts.

Another object is to provide an improved oscillating lever-operated automatically reversible pawl-and-ratchet involute slotted cam mechanism capable of compact side mounting between the removable unit and the cubicle and of obtaining the powerful mechanical advantage necessary for an operator to engage and disengage the disconnect contacts of a relatively large circuit breaker by effecting progressive movement of the unit both to and from the connected position upon oscillation of the operating lever, and also capable of securely locking the unit with the circuit breaker in the connected position.

Another object is to provide improved cooperating interlocking means for insuring that the circuit breaker is always tripped before the automatically reversible pawl can engage the ratchet to produce either the insertion or withdrawal movement of the unit.

Another object is to provide an improved manually operable oscillating lever type of drawout and interlocking mechanism that can readily be operated from the front of the unit or cubicle and requires only a very narrow mounting space between the sides of the enclosing cubicle and the sides of the switchgear unit on which the essential cooperating parts can be mounted with the rotatable involute cam and oscillatable lever either on the unit or on the cubicle as desired.

In the preferred form of the invention, a pair of rotatable disk-like slotted cam members are mounted on opposite sides of the removable switchgear unit and interconnected for joint rotation by means of a shaft extending across the back of the unit in order to produce balanced drawout and insert forces. Each cam member projects from the back of the unit and has an open end involute cam slot formed therein to engage with a cooperating camming pin fixed inside the cubicle. This improved camming construction enables a relatively long and powerful operating lever to be mounted coaxially adjacent one of the jointly rotatable cam members so as to extend from the back to be readily accessible for operation at the front of the switchgear unit. The long lever operates a reversible pawl to successively engage with two-way ratchet elements preferably formed on the periphery of the adjacent rotary cam member to effect progressive rotation thereof in either direction upon oscillation of the operating lever and means are provided for automatically reversing the pawl at the end of rotation in each direction. Thus, even a large circuit breaker unit having strong spring pressed disconnect contacts of large current carrying capacity, such as to require a very large force to effect engagement and disengagement thereof, can be moved progressively step-by-step to and from its connected position inside the cubicle, with only a normal manual force applied to "pump" the free end of the operating lever due to the very high force multiplying action provided by the long operating lever, the very high distance multiplying action provided by the

2

pawl-and-ratchet mechanism, in conjunction with the final increased force multiplying camming action of the involute cam slot formed in the rotatable cam member. Furthermore, the improved involute cam slot and pin combination will inherently mechanically lock the unit in its connected position with the pin engaged with the inner end of the involute cam slot when made substantially tangential to the axis of the rotatable cam member, thus effectively insuring against any accidental movement of the unit from its inserted or connected position.

In addition, the necessary interlocking for preventing insertion or withdrawal movement of the unit while the circuit breaker is closed is accomplished by providing a blocking member that is movable to the blocking position upon closure of the circuit breaker for preventing operative engagement of the pawl with the ratchet member. This blocking member cooperates with the pawl reversing means to completely free the pawl to prevent a withdrawal operation when the circuit breaker is closed and also renders it ineffective to produce an insert operation until the circuit breaker is opened.

Further objects and advantages of the invention will appear in the following description of the accompanying drawings, in which Fig. 1 is a side view of a removable circuit breaker unit enclosed in a metal-clad cubicle with one side of the cubicle almost completely removed in order more clearly to show the detailed structure and arrangement of the preferred form of the reversible ratchet cam drawout and interlock mechanism of the present invention. Fig. 2 is an enlarged view of the interlock mechanism that locks the door of the cubicle closed when the circuit breaker unit is in its normal operating connected position as shown in Fig. 1 and the circuit breaker is closed. Fig. 3 is a partial sectional view on the line 3—3 of the interlock mechanism shown in Fig. 2. Figs. 4, 5 and 6 are schematic side views showing the relative positions of the various operating parts as the circuit breaker unit is moved out of its enclosing cubicle. Figs. 7 and 8 show a modification of the improved drawout mechanism wherein interlocking is obtained by preventing operative engagement of the pawl with the ratchet when the circuit breaker is closed as indicated in Fig. 8.

As shown in Fig. 1, the removable circuit breaker unit, indicated generally by the reference character 10, includes a carriage 11 that is provided with a suitable frame structure 12 for carrying the insulating base 13 upon which the operating parts of the circuit breaker 14 are mounted. The circuit breaker 14 may be of any type but is shown as provided with a main and arcing contact sequential operating mechanism 15 of the improved type more fully described and claimed in the patent application Serial No. 137,411, now Patent No. 2,581,181, filed January 7, 1950, by John A. Favre and assigned to the assignee of the present invention. This circuit breaker mechanism is of the overload current responsive trip-free multiple-toggle type so that the circuit breaker may be closed by an energy-storing motor-operated mechanism 16 of the improved type more fully described and claimed in the patent application Serial No. 196,075, now Patent No. 2,667,076, filed November 16, 1950, by John A. Favre and assigned to the assignee of the present invention. In addition to the usual automatic overload current responsive trip, the circuit breaker mechanism 15 also is provided with the separate manual and safety interlock trip pin 19.

The enclosing cubicle 20 for the circuit breaker unit 10 is provided with a vertically hinged door 21 having a manually operable catch 22, that will engage behind the inturned edge of the side of the cubicle 20 that is not shown but entirely removed in Fig. 1, so as to reveal all of the parts in cooperating relation inside the cubicle. Thus, it will be understood that the several rollers 24 that support the carriage 11 of the circuit breaker unit 10 are in fact supported by a channel mounted on the side of the cubicle that is removed. Likewise, the manually operable push button 25 that is mounted on the slideable rod 26 is carried in the bracket 27 that is also mounted on the removed side of cubicle 20. The rod 26 is operatively connected with the lever 27 to raise the link 28 and engage finger 29 with the circuit breaker trip element 19,

and thereby manually open the circuit breaker 14. The removed side of cubicle 20 also carries the pins 17 that slidably mount the interlock channel 17 having safety trip camming elements 31 and 32 with channel 17 interconnected with the door locking lever 33 that carries the pin 34 into locking engagement with the overhanging hook member 35 when the door 21 is closed.

The circuit breaker unit 10 is provided with an interlock operating lever 37 that is pivoted at one end on the fixed pin 38 with the other end of lever 37 slotted and connected by means of the pin 39 so as to rotate the lever 37 in the counterclockwise direction when the circuit breaker 14 is opened as shown in Fig. 1 and in the clockwise direction when the circuit breaker is closed. The sliding link 40 is mounted on unit 10 and operatively connected with the lever 37 at one end by means of the pin 41 and is provided at the other end with a locking finger 42 that engages in a notch 43 formed in the transversely sliding channel member 17, so as to securely lock the door 21 in the closed position when the circuit breaker is closed.

The circuit breaker removable unit 10 is provided with suitable disconnect contacts 50 that project from the back of the unit so as to be forced into firm circuit closing engagement with the circuit terminal contacts 51 that are mounted on the insulating supports 52 to extend through the back wall of the cubicle 20. As shown, the circuit terminal contacts 51 are composed of a plurality of resilient conducting fingers in annular socket form so as to be compressed together by means of the encircling springs 53 and thereby establish a firm conducting pressure engagement between the circuit breaker disconnect contacts 50 and the circuit terminal contacts 51. This pressure engagement inherently results in a considerable frictional load that requires a materially increased force amplification in order to enable manual operation of the removable circuit breaker unit 10 to and from the inserted or connected position in which it is shown in Fig. 1.

In accordance with the present invention, such increased force amplification is obtained by means of the relatively long manual operating lever 55, the rotatable involute slotted member or disk 56, and the pawl and ratchet operating connection between the lever and the cam, provided by the reversible pawl 57 and the series of two-way ratchet elements 58 formed on the periphery of the involute cam member 56. In the preferred form shown, one end of lever 55 is rotatably mounted on a shaft 60 that extends across the back of the circuit breaker unit 10 and is rotatably supported in suitable bearing brackets secured to the frame 12. Each end of the shaft 60 carries an involute slotted cam member 56 fixed to the end of the shaft by the locking tongue 61 and suitable welding so that both of the cam members 56 always rotate jointly in fixed angular relation on the shaft 60 to produce balanced camming forces. An involute cam slot 63 is formed in each cam member 56 to span the axis thereof and progressively amplify the camming force with the inner end of the slot extending tangentially with respect to the axis of shaft 60 so as to engage with a pin 64 that is fixedly mounted on the removed side of the enclosing casing 20. By means of this involute cam construction, the removable switchgear unit 10 is securely locked in its inserted position with the disconnect contacts 50 held in firm current conducting engagement with the circuit terminal contact 51 as shown in Fig. 1. The outer end of the involute cam slot 63 is open so as to disengage the pin 64 and thereby effect the complete removal of the circuit breaker unit 10 from the enclosing casing 20.

The manual operating handle 55 is provided with a generally triangular shaped mounting plate 66 that is rotatably supported on the shaft 60 adjacent to the rotatable cam member 56, and the reversible pawl 57 is pivotally mounted adjacent one corner of the triangularly shaped member 66 to engage with the coaxial series of two-way ratchet elements 58 formed on the periphery of the rotatable slotted member or disk 56. As shown, the pawl 57 is mounted on pin 67 on which the double-ended centering spring 68 is coiled so that each end thereof may engage with either pin 69 on the pawl or pin 70 on the member 66 to always bias the pawl 57 and the pins into alignment with the pin 67.

DRAWOUT OPERATION

In order to draw out the circuit breaker unit 10 from

its insert or connected position inside the enclosing cubicle 20 as shown in Fig. 1, the first requirement is to trip the circuit breaker 14 in case it is closed. Otherwise, as long as the circuit breaker 14 remains closed, the finger 42 on link 40 will engage the notch 43 and lock the door 21 in the closed position, thereby effectively preventing access of an operator to the drawout operating handle 55. By pushing the push button 25 to lift the finger 29 carried by link 28 into engagement with the trip pin 19 the tripping of the circuit breaker operating mechanism 15 may be effected. When the circuit breaker is opened as shown, the door catch 22 may be operated to open the door so that the operator can then apply force to lift the operating lever 55, which normally rests against the stop pin 70 on the breaker unit. Thus, upon lifting the lever 55, pawl 57 will engage the end one in the series of two-way notching elements 58 formed on the periphery of the rotatable cam member 56, and thereby effect the first step in the joint rotation of both of the cam members 56 in the clockwise direction. When the operating lever 55 is thus raised as far as the door opening into the cubicle 20 permits, or as far as may be convenient for the operator, a powerful camming force will be exerted by the involute cam 63 on the fixed pin 64 so as to start the disengagement of the disconnect contacts 50 from the terminal contacts 51. The locking latch 71 that is pivoted on the frame 12 is held in an inactive position as shown due to the engagement of the upper arm 72 of latch 71 with the pin 73 that is fixed on the removed side wall of the cubicle 20. Upon lowering of the operating lever 55, the pawl 57 is returned to engage with a subsequent one of the two-way ratchet element 58 so that by repeated lifting and lowering of the lever 55, cam member 56 is progressively rotated in the clockwise direction. Thus, by the repeated "pumping" or oscillation of the operating lever 55, the rotatable cam 56 can be progressively rotated in the clockwise direction to cam the disconnect contact 50 entirely out of engagement with the terminal contacts 51 until the open end of the cam slot 63 is reached as shown in Fig. 4. Thereupon, the carriage 11 may be rolled out on the rollers 24 until the carriage is stopped in the test position, as shown in Fig. 5, by a suitable releasable stop (not shown), wherein the trip pin 19 lies in the valley between the tripping cams 31 and 32. Thus, in the test position, the trip pin 19 drops down from the cam 32 into the valley, and thus enables the circuit breaker mechanism to be closed and opened as desired to inspect or test for proper operation, since the circuit breaker unit 10 is entirely disconnected from the circuit. The parts then occupy their relative positions shown in Fig. 5, with the notched latch 71 in engagement with the pin 74 so as to hold the rotatable cam member 56 with its open end in proper aligned position for re-engagement with the fixed camming pin 64. Upon release of the stop (not shown), the circuit breaker unit 10 then may be rolled out to its outermost extended position as shown in Fig. 6, from which it may be removed and, if desired, another unit substituted therefor.

During the withdrawal camming action, accidental rotation of the shaft 60 in either direction is effectively prevented by a spring brake member 76, which is pressed against the shaft 60 by the compression springs 77 to restrain rotation of the rotatable involute slotted member or disk 56 in either direction upon disengagement of the pawl 57. With the cam parts in their relative position shown in Fig. 4, as soon as the operating handle is released so as to rest upon the stop pin 70, then the reversible pawl 57 is positioned opposite the pawl reversing notch or recess 78 that is formed in the periphery of the rotatable cam member 56 as shown.

Insert operation

To insert the switchgear unit 10 into its connected position inside of the enclosing cubicle 20, the carriage 11 is manually pushed on the rollers 24 until the open end of the cam slot 63 stops against the fixed pin 64, which is the position shown in Fig. 4. In this position, the latch 71 is disengaged from pin 74 and the circuit breaker trip pin 19 has been raised out of the valley onto the cam 32 and thereby effectively insures that the circuit breaker is open. To force the disconnect contacts 50 into circuit closing engagement with the circuit terminal contacts 51, the operating handle 55 is raised from stop 70

thereby automatically reversing pawl 57 in notch 78 so that the pawl can engage with the end two-way notching element 58 for operation in the insert direction. Thereupon a downward force exerted on the lever 55 will rotate the cam member 56 in the counterclockwise direction to produce a camming action between the involute cam slot 63 and the fixed pin 64 that will exert an amplified force sufficient to force the interengagement of the disconnect contacts 50 with the terminal contacts 51. By repeatedly pumping or oscillating the operating lever 55, a progressive rotation of the cam member 56 is obtained until the circuit breaker unit 10 is returned to its fully connected position and the pawl 57 is automatically reversed by the open end of slot 63 and returned to the position in which it is shown in Fig. 1.

However, the circuit breaker must always remain opened until the door 21 of the cubicle is closed. This is due to the operation of the interlocks shown in Fig. 2, since the tension spring 80 will draw the sliding interlock channel 17 to the right and thereby maintain the cam element 32 under the circuit breaker tripping pin 19 and hold this pin in position to insure that the circuit breaker is tripped. Upon closing the door 21, the hooked bracket 35 will engage with pin 34 and thereby move the interlock link 17 to the left into its position in which it is shown in Fig. 1, wherein the closure of the breaker will effectively lock the door closed and wherein the cam 32 is moved out from under the trip pin 19, so as to enable a closure of the breaker to be obtained.

In the modified form of drawout cam mechanism shown in Figs. 7 and 8, the rotatable cam member 56a is of somewhat different configuration and the reversible pawl 57a is provided with a weighted end to produce the centering thereof. Furthermore, and more important, interlock means in the form of the pivoted member 85 is provided for preventing operative engagement of the pawl 57a with the series of peripheral two-way ratchet elements 58a while the circuit breaker is closed. To accomplish this, the pawl interlocking member 85 is pivotally supported on the frame 12 by the pin 86 and is arranged to be operated to the position in which it is shown in Fig. 7 by the pin 87 that is carried on the sliding link 40 to the position shown in Fig. 8 when the circuit breaker 14 is closed.

Also as shown in Fig. 7, a modified form of latch member 71a is pivotally mounted on the pin 90 extending from the frame 12 and carries a latching pin 91 into a cooperating notch 92 provided on cam member 56a so as to hold the rotatable cam member 56a in the predetermined position wherein the pin 64 that is fixed inside the enclosing cubicle will engage with the open end of the involute cam slot 63a. The latch member 71a is provided with an integral cam surface 93 for engaging with the fixed pin 64 when the switchgear unit 10 is rolled into the enclosing cubicle 20 so as to raise the latch member 71a to its released position shown in Fig. 7 before the fixed pin 64 engages with the lip 94 formed at the open end of the involute slot 63a to stop the rolling insert movement of the switchgear unit 10 with the fixed pin 64 in position to be engaged by the involute slot 63a upon clockwise rotation of the rotatable cam member 56a. However, the latch pin 91 still engages with the back wall 95 of the notch 92 so as to prevent any clockwise rotation of the cam member 56a.

A further feature of latch member 71a is its function to prevent handle 55 from being operated when unit 10 is cammed out to test position or beyond. At test position latch member 71a is disengaged from pin 64 permitting its fall to engage pin 91 with slot 92. In this position, notch 100 is in line with projection 101 on handle 55. Raising handle 55 will cause projection 101 to engage with notch 100 before reversible pawl 57a engages with first notch 58a on cam 56a. This prevents destructive forces from being applied to pawl 57a while cam 56a is locked by pin 91.

Operation

With the modified drawout parts in their respective positions shown in Fig. 7, the circuit breaker unit 10 is ready for camming to the connected position since the circuit breaker is open. If, however, the circuit breaker were closed, the interlock member 85 would be moved into its blocking position so as to tilt the pawl 57a to its inclined or tilted position as shown in Fig. 8. In such

case, when the operating lever 55 is raised, the pawl 57a can only engage with the end two-way ratchet element 58 in such a manner as to continue rotation of the cam member 56a in the clockwise direction. However, such rotation will be effectively prevented by engagement of the latch pin 91 with the side wall 95. Upon return of the operating lever 55 into engagement with stop 70, the pawl 57a is returned to its tilted position in which it is shown in Fig. 8. In this way the interlock member 85 will effectively prevent any operative engagement of the pawl with the ratchet elements until the circuit breaker is opened.

Upon opening of the circuit breaker 14, the link 40 is lowered and carries the pin 87 to rotate the interlock member 85 to its inactive position as shown in Fig. 7, thereby freeing the weighted pawl 57a to return to its upright position as shown. Consequently, when the operating lever 55 is now raised from the stop 70, pawl 57a is automatically reversed into its oppositely inclined position so as to enable the pawl to operatively engage with the end one of the series of two-way notching elements 58a in the direction to rotate the cam member 56a in the counterclockwise direction and thereby engage the involute slot 63a with pin 64 to cam the switch gear unit toward its insert or connected position. By repeated "pumping" or oscillation of operating lever 55, the successive two-way notch elements are engaged to progressively rotate the cam members 56a in the counterclockwise direction until the fixed pin 64 reaches the closed end of the involute slot with the switchgear unit in its final connected position. In this position when the handle is raised, the pawl is disengaged from the last one in the series of two-way notching elements and due to its weighted end returns to the upright position. Thus, when the operating lever 55 is returned into engagement with stop 70, the pawl 57a will occupy a less tilted position than that shown in Fig. 8 and will be biased to engage the end one of the two-way notching elements 58a to rotate the cam element 57a in the opposite direction.

But upon closure of the circuit breaker with the unit 10 in its final connected position as shown in Fig. 8, the interlock member 85 is moved to engage with the weighted end of the pawl 57a and thereby further tilt the pawl into the ineffective position in which it is shown in Fig. 8. Now, in case operating lever 55 is raised while the circuit breaker is thus closed, the pawl 57a is prevented from operative engagement with the end one of the two-way ratchet elements 58a. In this way, the interlock member 85 prevents operative engagement of the pawl with the ratchet elements until the circuit breaker is opened. When this occurs, the pawl can then be brought into operative engagement with the end to a ratchet element and the repeated "pumping" of the operating lever 55 will rotate the cam member 56a in the clockwise direction to cam the switchgear unit 10 out of its connected position.

The force amplification provided by the relatively long lever 55, the distance amplification provided by the ratchet 58a and reversible pawl 57a, and the further force amplifying action of the involute cam slot 63a enable the disengagement of the disconnect contacts 50 of the circuit breaker unit to be disengaged from the terminal contacts 51 inside the cubicle 20 with only a normal force applied to the end of the operating lever 55. As soon as the pin 64 reaches the open end of the involute slot, the switchgear unit can easily be rolled out of the cubicle. Thereupon, the latch pin 91 of the latch member 71a is returned into locking engagement with the notch 92 in the rotatable cam member 56a so as to hold this member in the predetermined position required for re-engagement of pin 64 with the open end of the involute slot when the switchgear unit is reinserted in the cubicle.

In order to protect against any variation in the normal insert and withdrawal operation of the switchgear unit, as, for example, when an unskilled operator attempts to close the breaker when the unit is only half way inserted or withdrawn, a trip pin interlocking cam arrangement involving the cams 31 and 32 may be provided as shown in Fig. 1, if desired. However, it will be observed that in both the cam arrangement of Fig. 1 and the modified arrangement of Fig. 7, the insert operation is obtained by pushing down on the operating lever 55 with the upstroke idling, while the withdrawal operation is obtained by lifting up on the operating handle 55 with the

downstroke idling. In each case, the cam is provided with means for automatically reversing the pawl at the end of each insert or withdrawal operation, thereby automatically conditioning the pawl to perform the reverse operation upon subsequent oscillation of the operating lever 55.

It will be apparent that, if desired, instead of mounting the rotatable involute cam and the oscillating lever and reversible pawl and ratchet mechanism on the removable switchgear unit itself and the cooperating cam pins on the inside of the cubicle as shown and described, the respective mounting of these parts may just as well be reversed with suitable rearrangement thereof to maintain the same principles of cooperation therebetween. In the case of such reversal in the mounting of the parts of the modified form of the invention shown in Figs. 7 and 8, a suitable separable linkage mechanism may be provided, partly on the unit and partly on the cubicle, for effecting the movement of the blocking member to prevent operative engagement of the reversible pawl with the ratchet whenever the circuit breaker is closed with the unit in its connected position and also in its disconnected test position inside the cubicle. Thus the basic pawl blocking interlocking principle remains the same.

What I claim as new and desire to secure by Letters Patent of the United States is:

1. A movable carriage unit force-amplifying operating mechanism having in combination a rotatable member provided with an open end involute cam slot spanning the axis of the member and with a coaxial series of two-way ratchet elements, a cooperating member engageable with the opposite edges of the involute cam slot to move the unit in opposite directions upon corresponding rotation of the rotatable member, and an operating lever pivoted coaxially with the rotatable member and having a reversible pawl for engaging the ratchet elements to rotate the member progressively in either direction upon oscillation of the lever.

2. A movable carriage unit force-amplifying operating mechanism having in combination a centrally pivoted rotatable member provided with an open end involute cam slot spanning the axis of the member and with a coaxial series of two-way ratchet elements, a cooperating member engageable with the involute cam slot to move the unit each way between two positions upon corresponding rotation of the rotatable member, an oscillatable operating lever pivoted coaxially with the rotatable member and having a reversible pawl for successively engaging the ratchet elements to rotate the member progressively in either direction upon oscillation of the lever, and means effective in each position of the unit for reversing the pawl in response to pivotal movement of the operating lever.

3. A removable carriage unit force-amplifying operating mechanism having in combination a rotatable member on the unit provided with an open end involute cam slot and with a series of peripheral two-way ratchet elements, a fixed member engageable with the open end of the involute cam slot in a predetermined angular position of the member to move the unit in one direction upon corresponding rotation of the cam member and in the opposite direction upon reverse rotation of the cam member, an oscillatable operating lever pivoted on the unit coaxially adjacent the rotatable member and having a reversible pawl for engaging the peripheral ratchet elements to rotate the member progressively in either direction upon oscillation of the lever, and means including a latch biased upon removal of the unit from the fixed member to hold the rotatable member in the predetermined angular position on the unit and releasable upon engagement of the fixed member with the open end of the slot.

4. A removable carriage unit insert and drawout mechanism having in combination a rotatable cam member provided with an involute cam slot spanning the axis of said member having the inner end thereof extending substantially tangentially with respect to the axis of the rotatable member and the outer end thereof open, a cooperating member engaged with the inner end of the involute cam slot to lock the unit in the insert position and to move the unit upon rotation of the cam member between the insert and drawout position wherein the cooperating member is releasable from the open end of the slot to effect removal of the carriage unit and an oscillatable operating lever pivoted coaxially with the rotatable member and having a reversible pawl and ratchet

connection with the cam member to rotate the member progressively in either direction upon oscillation of the lever.

5. A removable carriage unit insert and drawout mechanism having in combination a pair of interconnected jointly rotatable disks spaced apart to receive the unit therebetween and each provided with an open end involute cam slot spanning the axis of the disk, one of said disks having a series of peripheral two-way ratchet elements, a pair of spaced apart cooperating members, each engageable with the involute cam slot of a corresponding disk to move the unit upon joint rotation of the disks between the insert and drawout position wherein each cooperating member is releasable from the open end of the corresponding slot to effect removal of the unit, and an oscillatable operating lever pivoted coaxially with the one rotatable disk and having a reversible pawl for successively engaging the peripheral two-way ratchet elements of the one disk to rotate both cam disks progressively in either direction upon oscillation of the lever.

6. In combination, a removable switchgear unit having disconnect contacts, a housing unit for the switchgear unit having disconnect contacts therein, a rotatable member on one of the units having an open end involute cam slot formed therein, a pin mounted on the other unit for releasably engaging the cam slot to effect relative movement of the unit in opposite directions upon corresponding rotation of the member to engage and disengage the disconnect contacts inside the housing, means including a reversible pawl and ratchet for rotating the member each way, and means restraining rotation of the rotatable member in either direction upon disengagement of the pawl.

7. In combination, a removable switchgear unit having disconnect contacts extending from the back thereof, a housing for the unit having circuit terminal contacts extending through the back thereof, a rotatable member extending from the back of the unit and having an open end involute cam slot formed therein, a pin mounted inside the housing for engaging with the open end of the cam slot to move the unit in opposite directions upon corresponding rotation of the member to engage and disengage the disconnect contacts with the circuit terminal contacts inside the housing, and means including a reversible pawl and ratchet mechanism having an operating lever mounted coaxially adjacent the rotatable member and extending to the front of the unit for rotating the member each way.

8. In combination, a removable switchgear unit having disconnect contacts, a rotatable member mounted on the unit and provided with a series of two-way ratchet elements and with an involute cam slot spanning the axis of said member and having the inner end thereof extending substantially tangentially with respect to the axis of the rotatable member and the outer end thereof open, a housing having cooperating circuit terminal contacts therein and provided with a fixed member engaged with the inner end of the involute cam slot to lock the unit in the insert position with the disconnect contacts and cooperating circuit terminal contacts in circuit closing engagement and to move the unit upon rotation of the cam member between the insert and drawout position wherein the fixed member is releasable from the open end of the slot to effect removal of the unit from the housing, and an oscillatable operating lever pivoted on the unit coaxially with the rotatable member and having a reversible pawl for successively engaging the ratchet elements to rotate the member progressively in either direction upon oscillation of the lever.

9. In combination, a circuit breaker unit having insert and drawout mechanism provided with reversible pawl and ratchet operating means, and interlock means controlled by the circuit breaker for preventing operative engagement of the pawl with the ratchet when the circuit breaker is closed.

10. In combination, a metal cubicle having circuit terminal contacts therein, a removable circuit breaker unit having disconnect contacts for engaging and disengaging the circuit terminal contacts upon reverse movements of the element in the cubicle, a member rotatably mounted on one side of the unit and having an open end involute cam slot formed therein and provided with peripheral two-way ratchet elements, a pin extending from the corresponding side of the cubicle for engaging the cam slot to effect the reverse movements of the unit upon

corresponding reverse rotation of the member, an oscillatable operating lever pivoted concentrically with the rotatable member and having a reversible pawl for successively engaging the ratchet elements to rotate the member progressively in either direction upon oscillation of the lever, and interlocking means for preventing operative engagement of the pawl with the ratchet when the circuit breaker is closed.

11. In combination, a metal cubicle having circuit terminal contacts therein, a removable circuit breaker unit having disconnect contacts for engaging and disengaging the circuit terminal contacts upon reverse movements of the unit inside the cubicle, a pair of interconnected cam members jointly rotatable on opposite sides of the unit and each having an open end involute cam slot formed therein and one of the members having peripheral two-way ratchet elements, latch means for holding the members in a predetermined angular position upon removal of the unit, a pin extending from the corresponding side of the cubicle for releasing the latch and engaging the open end of a corresponding cam slot in the predetermined angular position of the members upon reinsertion of the unit into the cubicle to effect said reverse movements of the unit upon corresponding reverse rotation of the members, an oscillatable operating lever pivoted coaxially adjacent the one rotatable member and having a reversible pawl for successively engaging the peripheral two-way ratchet elements thereon to rotate the member progressively in either direction upon oscillation of the lever, and interlocking means including a blocking member movable upon closure of the circuit breaker for preventing operative engagement of the pawl with the ratchet.

12. A movable unit operating mechanism having in combination a centrally pivoted rotatable disk provided with an open end involute cam slot extending between diametrically opposed points on the disk and with a series of two way ratchet elements in the periphery of the disk, a cooperating member engageable with the opposite edges of the involute cam slot to move the unit in opposite directions upon corresponding rotation of the disk and an operating lever pivoted coaxially adjacent the disk and having a reversible pawl for engaging the peripheral ratchet elements to rotate the disk progressively in either direction upon oscillation of the lever.

13. A movable unit operating mechanism having in combination a rotatable member provided with an open end involute slot spanning the axis of the member and with a coaxial series of two way ratchet elements, a cooperating member engageable with the opposite edges of the involute cam slot to move the unit in opposite directions upon corresponding rotation of the rotatable mem-

ber, an operating lever pivoted coaxially adjacent the rotatable member and having a reversible pawl for engaging successive ratchet elements to rotate the member progressively in either direction upon oscillation of the lever, and means restraining rotation of the rotatable member in either direction upon disengagement of the pawl.

14. In combination, a removable unit having a member rotatably mounted thereon adjacent the inner side thereof and provided with an open end involute slot spanning the axis of the member and with a coaxial series of two way ratchet elements, a stationary member engageable with the opposite edges of the involute cam slot to move the unit in the insert and drawout directions upon corresponding rotation of the rotatable member, and an operating lever mounted on the unit coaxially adjacent the rotatable member to project for oscillation beyond the outer side of the unit and having a reversible pawl for engaging successive ratchet elements to rotate the member progressively in either direction upon oscillation of the lever.

15. A movable unit operating mechanism having, in combination, a rotatable member provided with a cam slot and with ratchet structure comprising a series of ratchet elements which extend between circumferentially spaced points on said rotatable member, a cooperating member engageable with said cam slot to move said unit each way between two positions upon corresponding rotation of the rotatable member, an oscillating operating lever pivoted coaxially with respect to said rotatable member and having a reversible pawl for successively engaging the ratchet elements to rotate the rotatable member progressively in either direction upon oscillation of the lever, and means effective in each of said two positions of the unit for reversing the pawl in response to pivotal movement of the operating lever, said means being characterized by the portion of said ratchet structure adjacent said circumferentially spaced points being recessed radially inwardly by an amount sufficient to permit reversing of said pawl when said pawl is positioned opposite said recessed portion.
